BILGE KEEL OR THE LIKE ANTIROLLING DEVICE FOR SHIPS

Application filed April 11, 1930, Serial No. 443,495, and in Great Britain April 16, 1929.

This invention relates to anti-rolling devices for ships. The primary object of the invention is to provide such a device which in addition to being more effective in reducing the rolling of ships than the bilge keels hitherto used, simultaneously presents less resistance to forward movement and develops a forward reaction assisting the propulsion of the vessel when rolling, pitching or heaving.

Hitherto, bilge keels have been made of various forms and cross-sections but all have extended continuously over a substantial portion of the length of the vessel. Their action is identical with that of aerofoils of very low aspect-ratio, since when the vessel is moving ahead and simultaneously rolling, pitching or heaving, the resultant flow velocity on to such keels is inclined to their forward translational direction at an angle corresponding to that of the resultant of the vessel's forward velocity and the transverse velocities due to rolling, pitching or heaving. Under such flow conditions a transverse force is induced on the keels and is at right angles to a direction subtending an angle with the forward direction something less than half that subtended by the resultant velocity. This transverse force thus has a forward component, but owing to the very low aspect-ratio of the keels hitherto used and their non-streamline form, the induced transverse force is relatively low as is also its angle of forward inclination, and consequently its forward component is very small compared with the sternward resistance of the keels. To improve these conditions by increasing the depth of such keels, thereby increasing their aspect-ratio and the forward inclination of the induced transverse force is, moreover generally impracticable.

It has been proposed to fit two or more rows of bilge keel sections with gaps therebetween in staggered relation at each bilge. Such arrangement is incapable of developing a forward component of the forces acting thereon during rolling while the increased wetted surface adds appreciably to the skin friction resistance to forward motion of the vessel.

The present invention consists in an anti-

rolling device for ships comprising a plurality of relatively short bilge keels of symmetrical streamline form with rounded nose and tapering run aft spaced apart at intervals longitudinally on each bilge of the ship and structurally connected therewith. Said short bilge keels are preferably made with their maximum cross section at about one-third of their length from the nose.

The greatly increased aspect-ratio of such improved keels will still be small as compared with that of an efficient aerofoil. An improvement in this respect is effected by fitting the keels along their outboard edge with "flow-caps" that is, each with a plate substantially parallel to the hull surface. These flow-caps prevent equalization of pressure round the outboard edge of the keel, and thereby virtually increases the aspect-ratio. Therefore the invention also consists in a plurality of relatively short bilge keels each provided with a flow-cap along its outboard edge.

Drawings are appended diagrammatically illustrating the invention as carried into effect in one form by way of example.

Figure 1 is an elevation, and Figure 2 a half transverse section, of a ship fitted with a plurality of short bilge keels according to the invention.

Figures 3, 4 and 5 are views showing the form of one of the short bilge keels, Figure 3 being an elevation on the plane of symmetry of the keel, which plane is that of the natural hull stream lines and is thus normal or nearly so to the surface of the hull of the vessel, Figure 4 a section at its base at the skin-plateing of the hull, and Figure 5 a transverse view looking aft.

Figure 6 shows a detail.

Figure 7 is a diagram illustrating the action of the bilge keels made according to the invention.

The short bilge keels 1 are fixed to the hull in rows, one row on each side of the ship where long continuous bilge keels have usually been fitted according to present day practice. The streamline form of the keels is best shown in Figure 4. The preferred form comprises a rounded nose, maximum cross-

section 4 at or near one-third the length from the nose, and sides 5 with a tapering run aft from the maximum section 4 to the tail 6. In cross-section (Fig. 5), the sides 5 taper from a maximum width at the base 7 of the keel 5 at the hull of the ship to a minimum width at the outboard edge 8. A flow-cap or plate 9 is preferably fitted to the outboard edge of each keel substantially parallel to the base 10 thereof at the hull surface. Structurally, in the form illustrated, the bilge keels are made of steel plates 10, angle-bars 11 which are riveted to the hull of the vessel, and a T-bar forming the flow-cap 9. Transverse dia- 15 phragm plates may also be fitted at intervals; one is shown at 2 where the nose plate 3 is welded to the side plates 10, and another at or near the maximum cross section 4. The weld joint of nose plate 3, side 10 and dia- 20 phragm plate 2 is shown in section in Figure 6.

In a modification, the rounded nose 3, which is the leading edge of the keel, may be arranged in elevation (Fig. 3) to slope aft 25 as well as outwards from the hull, so that no obstruction be offered to submerged seaweed or wreckage flowing past.

To guard against internal corrosion, the bilge keels may be filled with pitch or other 30 suitable material.

Such improved keels, due to their stream-line form, have a low resistance to motion ahead and induce a high transverse force when the vessel is moving ahead and simultaneously rolling, pitching or heaving. 35 Their greater aspect-ratio further increases this transverse force and also its forward inclination, so that the forward component of the force is such that it now exceeds the relatively low sternward resistance of the keel 40 and thus acts to propel the vessel. This is diagrammatically illustrated in Figure 6, wherein, following aerofoil theory, the vector a represents the forward speed of the ship, b the linear speed of rolling, and c the speed 45 of the water flow relative to the bilge keel before reaching it. The line d represents the reaction of the water on the bilge keel, and being at right angles to a vector intermediate 50 between a and c depending on the aspect-ratio of the keel, has thus a forward component whose magnitude is the greater the greater 55 the aspect-ratio of the keel.

Consequently from the adoption of such 55 improved keels the following advantages will accrue:

The resistance of the ship to rolling, pitching and/or heaving, (and oscillating motions generally) is greatly increased and consequently the amplitudes of such oscillations 60 are reduced. In all vessels, but particularly in passenger vessels, this reduction in oscillating motion adds to the comfort of life on board; in war vessels it results in a steadier gun platform; and in all vessels it reduces the 65

loss in speed otherwise occasioned by such oscillating motion. Owing to the transverse force induced on the keels having a forward component, some of the external energy causing the ship to oscillate is made available for the propulsion of the ship. In other words, the keels scull their way through the water and hence deliver a useful thrust, thus further reducing the speed loss previously mentioned. 75

Finally, the greatly reduced aggregate length of keels made possible by the present invention results in reduced weight and cost. The wetted surface of the keels is simultaneously greatly reduced and this in combination with their efficient stream-line form, results in a corresponding reduction in their resistance to motion ahead. 80

I claim:

1. An anti-rolling device for ships comprising a plurality of relatively short bilge keels of symmetrical stream-line form with rounded nose and tapering run aft spaced apart at intervals longitudinally on each bilge of the ship, said bilge keels being provided with flow-caps at their outboard edges substantially parallel to the hull surface. 85

2. In a ship, a plurality of relatively short bilge keels of symmetrical stream-line form with rounded nose and tapering run aft and of cross sections tapering from a maximum width at their bases at the hull surface to a minimum near their outboard edges, said bilge keels being provided with flow-caps at 90 their outboard edges substantially parallel to the hull surface. 100

3. An anti-rolling device for ships as claimed in claim 2, wherein said bilge keels are hollow riveted steel structures each comprising steel plate sides, a steel plate nose, a T-bar having its web riveted between said sides at their outboard edges, and angle-bars riveted to said sides at their inboard edges and to the hull of the ship. 105

In testimony whereof I affix my signature. 110

E. V. TELFER.
